CLOTHES SUPPORTING ROD FOR A DISPLAY STAND OR THE LIKE

Arthur Garson, New York, N.Y., assignor to Wahl Associates, Inc., Long Island City, N.Y., a corporation of New York

Filed Nov. 13, 1967, Ser. No. 9,361

Term of patent 14 years

U.S. Cl. D80—8

Int. Cl. D6—07

FIG. 2

FIG. 1 is a top view of a clothes supporting rod for a display stand or the like showing my new design; and FIG. 2 is a front elevation view thereof.

The broken line representation of a display stand in FIGS. 1 and 2, is for purposes of illustration only.

I claim:

The ornamental design for a clothes supporting rod for a display stand or the like, substantially as shown and described.
